Coleman Sudol Sapone, P.C.

(57) **CLAIM**

The ornamental design for a hearing aid, as shown and described.

DESCRIPTION

FIG. 1 is a front elevational view of a hearing aid, showing our new design;

FIG. 2 is a rear elevational view thereof;

FIG. 3 is a top view thereof;

FIG. 4 is a bottom view thereof;

FIG. 5 is a left side elevational view thereof;

FIG. 6 is a right side elevational view thereof;

FIG. 7 is a perspective view thereof; and,

FIG. 8 is a side elevational view thereof, in use condition. The broken line showing is for illustrative purposes only and forms no part of the claimed design.
